UNITED STATES PATENT OFFICE.

ADOLPH BENNETT, OF NEW YORK, N. Y.

DESIGN FOR A NECKTIE.

47,097.

Specification for Design.

Patented Mar. 16, 1915.

Application filed December 11, 1914. Serial No. 876,737. Term of patent 3½ years.

To all whom it may concern:

Be it known that I, ADOLPH BENNETT, a citizen of the United States, and a resident of the city of New York, borough of Manhattan, in the county and State of New York, have invented a new, original, and ornamental Design for Neckties.

Reference is to be had to the accompanying drawings in which—

ing my new design; Fig. 2 is a section through Fig. 1 on line 2—2.

I claim:

The ornamental design for a necktie, as shown.

ADOLPH BENNETT.

Witnesses:

A. L. KITCHIN,
PHILIP D. ROLLHAUS.
